A. J. CORNELIUS,
PARACHUTE DROP,
APPLICATION FILED APR. 15, 1922.

Patented Nov. 14, 1922.
2 SHEETS—SHEET 2.

Fig. 1.

UNITED STATES PATENT OFFICE.

ARTHUR J. CORNELIUS, OF BUTLER, PENNSYLVANIA.

PARACHUTE DROP.

Application filed April 15, 1922. Serial No. 552,877.

To all whom it may concern

Be it known that I, ARTHUR J. CORNELIUS, a citizen of the United States, residing at Butler, in the county of Butler and State of 5 Pennsylvania, have invented new and useful Improvements in Parachute Drops, of which the following is a specification.

This invention relates to releasing means, and more particularly to what I term a parachute drop for use in connection with airplanes.

One of the main objects of the invention is to provide simple and efficient means whereby the passengers may be quickly and 15 safely discharged from an airplane in case of accident. A further object is to provide means of the character stated of simple construction and operation which may be readily installed. Further objects will appear 20 from the detailed description.

In the drawings:—

Figure 1 is a side view of the apparatus;

Figure 2 is a section taken substantially 25 on line 2—2 of Fig. 1, parts being omitted for clearness;

Figure 3 is a section taken substantially on line 3—3 of Fig. 1;

Figure 4 is a fragmentary section taken 30 through the seat and associated parts; Figure 5 is a detail of the connection between the operating rod and one of the catches.

In constructing the apparatus I provide a plurality of uprights 1 which are secured in 35 the fuselage A of the airplane, these uprights being arranged in squares or rectangles. A bracket 2 is secured to each upright by a bolt 3 and to the adjacent side of the fuselage. This bracket is provided with a depending sleeve 4 which accommodates an expansion coil spring 5 mounted about upright 1 and confined between the upper end of the sleeve and a collar 6 provided at the corner of a rectangular frame 7 to which is secured 40 to a seat 8, one seat being positioned between each set of uprights. The sleeves 6 provide a sliding mounting on uprights 1 which permit the seat to move downwardly when released. The seat 8 is normally held raised 45 by means of catches 9 which are pivoted on strips 10 secured to the inner face of the fuselage at each side thereof, these catches being normally in engagement with rectangular fingers 11 which project laterally from 50 sleeves 6. At their upper ends the catches 9 are pivotally secured in turn-buckles 12 con-

nected by rods 13. The front turn-buckle 12 is connected by a rod 14 to an operating lever 15 mounted on a bracket 16 secured to strip 10. The rearmost turn-buckle 12 is 60 connected by a rod 17 to a tension spring 18 secured to strip 10, this spring acting to normally hold the catches 9 in operative position. By pulling the upper arms of levers 15 rearwardly and upwardly catches 9 may 65 be moved into inoperative position so as to release the frames 7 thus permitting seats 8 to move downwardly along the uprights 1.

The bottom of fuselage A is provided, beneath the seats 8, with openings of relatively 70 great area. These openings are normally closed by rectangular closure members or doors 19 each of which is provided on its upper face with four cylindrical casings 20 having base flanges 21 secured to door 19 by 75 bolts 22 or in any other suitable or preferred manner. The lower portion of upright 1 fits into casing 20 and an expansion coil spring 23 is mounted in this casing and confined between the bottom of the same and 80 the lower end of the upright. These springs act to force the door 19 downwardly through the opening in the bottom of the fuselage. Each door is further provided, adjacent to each corner, with a hook member 24 secured 85 to the inner face of the door and adapted to be engaged by a catch 25 pivoted on a strip 26 secured to the side of the fuselage. The upper ends of the catches 25 are pivoted in turn-buckles 27 connected by rods 28. The 90 foremost turn-buckle is connected by a rod 29 to a foot lever 30 pivoted in a bracket 31 secured to the bottom of the fuselage. The rearmost turn-buckle is connected by an eye rod 32 to a tension spring 33 which is secured to strip 26.

As will be understood, there may be as many seats provided as desired and when the passengers enter the airplane they strap on parachutes of any known or preferred type. 100 The pilot of the airplane is preferably in the front seat and, in the event of an accident such as would be apt to cause falling of the airplane, he depresses levers 30 thus moving catches 25 out of engagement with hook 105 members 24. This releases the closure members or doors 19 which are forced downwardly by the expansion springs 23 so as to leave the openings through the bottom of the fuselage unobstructed. After this has been 110 done, the levers 25 are rocked rearwardly thus releasing seats 8 which, with the pas-

sengers, are discharged through the openings in the bottom of the fuselage, and the parachutes which have been previously strapped to the passengers, as above stated, 5 act to permit them to descend to the ground without danger of serious injury. Preferably I provide two foot levers and two hand levers positioned at each side of and adjacent to the forward seat, though any other 10 suitable or preferred arrangement for operating the releasing catches may be employed.

What I claim is:—

1. In means for releasing an airplane seat 15 so as to discharge from the airplane a person sitting upon the seat, spaced uprights, seats slidably mounted on the uprights for movement downwardly off of the same, closure members beneath the seats, means for 20 supporting said closure members and for releasing the same so as to provide unobstructed openings beneath said seats, means for exerting downward pressure on the seats, and means for supporting the seats and for 25 optionally releasing them.

2. In means for releasing an airplane seat so as to discharge from the airplane a person sitting upon the seat, a plurality of uprights disposed in spaced relation, a seat frame 30 slidably mounted on said uprights and freely movable downwardly off of the uprights, a seat carried by said frame, supporting members projecting from the frame, catches engaging with said supporting members and acting to normally hold the seat frame raised, and means for moving said 35 catches into inoperative position for releasing the seat frame so as to permit downward movement thereof off of the uprights.

40 3. In means for releasing an airplane seat so as to discharge from the airplane a person

sitting upon the seat, a plurality of uprights, a seat frame mounted on said uprights and freely movable downwardly off of the uprights, supporting fingers projecting from the frame, catches for engagement with said fingers, means for normally holding said catches in operative position, the catches acting to support the seat frame, and means for moving the catches into inoperative 50 position.

4. In means for releasing an airplane seat so as to discharge from the airplane a person sitting upon the seat, a plurality of uprights, a seat slidably mounted on the uprights and movable downwardly off of the same, a closure member of greater area than the seat and positioned beneath said seat, means for exerting downward pressure on said closure member, means for supporting 60 the closure member and optionally releasing the same, and means for supporting the seat and for releasing the same.

5. In means for releasing an airplane seat so as to discharge from the airplane a person sitting upon the seat, a plurality of spaced uprights, a seat slidably mounted on said uprights and movable downwardly off of the same, means for supporting said seat and for 65 optionally releasing the seat, a closure member of greater area than the seat and positioned beneath the same, securing members carried by said closure member, catches positioned and adapted for engagement with said securing members and acting to normally hold the closure member against 70 downward movement, and means for moving said catches into inoperative position so as to release the closure member.

In testimony whereof I affix my signature. 80

ARTHUR J. CORNELIUS.
